US0D1007502S

(12) **United States Design Patent** (10) **Patent No.:** **US D1,007,502 S**
(45) **Date of Patent:** **** Dec. 12, 2023**

(54) **TABLET COMPUTER**

(71) Applicant: **SAMSUNG ELECTRONICS CO., LTD.**, Suwon-si (KR)

(72) Inventors: **Dongkyun Kim**, Suwon-si (KR); **Namhyun Kang**, Suwon-si (KR); **Minah Koh**, Suwon-si (KR); **Mingeun Kim**, Suwon-si (KR); **Hakdo Kim**, Suwon-si (KR); **Sol Lee**, Suwon-si (KR)

(73) Assignee: **SAMSUNG ELECTRONICS CO., LTD.**, Gyeonggi-Do (KR)

(*) Notice: Patent file contains an affidavit/declaration under 37 CFR 1.130(b).

(**) Term: **15 Years**

(21) Appl. No.: **29/750,380**

(22) Filed: **Sep. 14, 2020**

(30) **Foreign Application Priority Data**

Jul. 2, 2020 (KR) 30-2020-0030273

(57) **CLAIM**

The ornamental design for a tablet computer, as shown and described.

DESCRIPTION

FIG. 1 is a front perspective view of a tablet computer, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The broken lines illustrating portions of the tablet computer form no part of the claimed design.

1 Claim, 6 Drawing Sheets
